UNITED STATES PATENT OFFICE.

LOUIS CHANDLER WITKOWSKI, OF WASHINGTON, DISTRICT OF COLUMBIA,
ASSIGNOR TO THE CROWN SELF-OPENING CAN COMPANY, OF WEST
VIRGINIA.

BOX OR CAN.

SPECIFICATION forming part of Letters Patent No. 625,626, dated May 23, 1899.

Application filed March 6, 1899. Serial No. 707,966. (No model.)

To all whom it may concern:

Be it known that I, LOUIS CHANDLER WITKOWSKI, a citizen of the United States of America, residing at Washington, in the District of Columbia, have invented certain new and useful Improvements in Boxes or Cans; and I do hereby declare the following to be a full, clear, and exact description of the invention, such as will enable others skilled in the art to which it appertains to make and use the same.

My invention relates to improvements in boxes or cans and to said boxes or cans provided with means for opening the same; and it consists of certain novel constructions, combinations, and arrangements of parts, as will be hereinafter fully described and specifically claimed.

In the accompanying drawings, Figure 1 is a perspective view of a box or can constructed in accordance with my invention and showing in dotted lines means for opening the same, the can being in condition for shipment. Fig. 2 is a perspective view of the same as it appears when being opened. Fig. 3 is a top plan view of the end of a can slightly modified in its construction to receive the opening means. Fig. 4 is a vertical transverse section through the same, and Fig. 5 represents portions of two cans when packed one upon the other.

A in the drawings represents a box or can constructed in accordance with my invention and which is provided with a closed end *a*, which latter is formed with depression-points, 35 pockets, or recesses *a'*, which depression-points are arranged preferably at different distances from the center of said end for the purpose now to be described. A can-opener *B*, constructed of thin sheet-steel, is designed 40 to be shipped with the can, and said opener is provided with a pivot-point *b* and a penetrating-point *b'*, as clearly shown in Fig. 4. The opener *B* is made of such a length that it will fall within the circumference of the end of 45 the can, so as not to project beyond the same during transportation, but during the cutting-out operation projects beyond the said outer edge to form a handle. One of the 50 pockets *a'* is designed to receive the pivot-point *b* of the opener and the other pocket is

designed to receive the penetrating-point *b'*, so as to avoid all liability of the can being punctured or any injury being done to the can packed on top. By arranging the pockets at different distances from the center of the 55 end of the can—that is, eccentrically thereto—a greater leverage can be secured for opening the can, for the reason that when the pivot-point and the cutting-point are lifted out of the pockets and the pivot-point is forced into 60 the can at a central point (indicated as at *a*² in Fig. 1) and the cutting-point caused to penetrate the said end very close to the periphery thereof a greater length of the can-opener will project beyond the outer edge of the can 65 than would be the case if the pockets or recesses were arranged at equal distances from the center—that is, concentrically thereto—as is obvious, and for this reason it is very important that the pockets be arranged in 70 this manner, and I regard it as an important feature of my invention. The same object would be accomplished by constructing a continuous groove, recess, or pocket eccentrically to the center of the end, as shown in Fig. 75 3, whereby two depressions would be secured.

In order to retain the can-opener in position on the can and avoid any liability of the same becoming disconnected therefrom and lost, the same may be held in place in any suitable 80 manner—as, for instance, by a label *D*, as shown in Fig. 1, or by having another can placed on top of the same, as illustrated in Fig. 5.

Where a label is employed, the same would 85 be found convenient for having printed on it the directions for opening the can, and where means are employed for holding the cutter in position on the can I do not wish to limit my invention to depression-points being arranged 90 eccentrically, as I believe I am the first inventor of a box or can provided with pockets or recesses to receive the pivot-point and cutting-point of a can-opener, said opener being designed to be shipped with the can and which 95 is held in place in said pockets during transportation.

Having now described my invention, what I claim as new, and desire to secure by Letters Patent, is—

1. A box or can provided with a closed end, which latter is formed with depression-points or pockets at unequal distances from the center, one of said depression-points being for the reception of the point of a cutter and the other for the reception of the pivot-point of a can-opener, substantially as described.
2. A box or can having a closed end which is formed with depression-points or pockets, 10 a knife or cutter located on said end, said knife or cutter being provided with a pivot-

point and a cutting-point which rest in the depression-points or pockets, and means for holding the said points in said depression-points, during transportation, substantially 15 as described.

In testimony whereof I hereunto affix my signature in presence of two witnesses.

LOUIS CHANDLER WITKOWSKI.
